CLAIM

The ornamental design for an combined electrical and cabling housing as shown and described.

DESCRIPTION

FIG. 1 is a perspective view of the combined electrical and cabling housing showing my new design;

FIG. 2 is front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged view of area 8 as indicated in FIG. 2. The dash-dash broken lines are for the purpose of illustrating portions of the article that form no part of the claimed design.

The dash-dot broken lines are for the purpose of defining the enlarged area and form no part of the claimed design.

1 Claim, 5 Drawing Sheets
